(57) **CLAIM**

The ornamental design for a visual signature reducer, as shown and described.

DESCRIPTION

FIG. 1 is a perspective view of the visual signature reducer in accordance with my invention;

FIG. 2 is a front end view thereof, taken from the left side of FIG. 1;

FIG. 3 is a back end view thereof, taken from the right side of FIG. 1;

FIG. 4 is a first side view thereof;

FIG. 5 is a second side view thereof;

FIG. 6 is a top view thereof; and,

FIG. 7 is a bottom view thereof.

Broken lines shown in FIGS. 1-7 are for illustrative purposes only and form no part of the claimed design. The surface indicia of parallel lines also form no part of the claimed design and are merely surface shading.
